UNITED STATES PATENT OFFICE

171,478

CLOCK

Rudolph M. Babel, Pawtucket, R. I., assignor to
General Electric Company, a corporation of
New York

Application September 25, 1953, Serial No. 26,958

Term of patent 14 years

(Cl. D42—7)

To all whom it may concern:

Be it known that I, Rudolph M. Babel, have invented a new, original, and ornamental Design for a Clock, of which the following is a specification, reference being had to the accompanying drawing, forming a part hereof.

In the drawing, Fig. 1 is a front perspective view of a clock embodying my new design, and Fig. 2 is a side elevational view.

I claim:

The ornamental design for a clock, as shown.
RUDOLPH M. BABEL
